PACKAGING AND DISPLAY CARTON FOR A POWER TOOL OR THE LIKE

Arthur L. Shreve III, Butler, Lyell Bayne Norris, Jr.,
Phoenix, and Robert W. Beichler, Baltimore, Md.,
assignors, by direct and mesne assignments, to The
Black and Decker Manufacturing Company, Towson,
Md., a corporation of Maryland

Filed Apr. 24, 1968, Ser. No. 11,599

Term of patent 14 years

Int. Cl. D9—04

U.S. Cl. D9—191

FIG. 1

FIG. 2

FIG. 4

FIG. 1 is a top perspective view of a packaging and display carton for a power tool or the like showing our new design, the opposite side being a mirror image of the side shown;

FIG. 2 is a bottom perspective view thereof;

FIG. 3 is a view similar to FIG. 1 but showing a modified form of our new design, the opposite side being a mirror image of the side shown; and

FIG. 4 is a bottom perspective view thereof.

We claim:

The ornamental design for a packaging and display

carton for a power tool or the like, as shown and described.
